UNITED STATES PATENT OFFICE

JEAN A. ROCHE, OF DAYTON, OHIO, ASSIGNOR TO THE AERONAUTICAL CORPORATION OF AMERICA, OF CINCINNATI, OHIO, A CORPORATION OF OHIO

DESIGN FOR AN AEROPLANE

Application filed July 25, 1929. Serial No. 32,200. Term of patent 14 years.

To all whom it may concern:

Be it known that I, JEAN A. ROCHE, a citizen of the United States of America, and a resident of Dayton, in the county of Montgomery and State of Ohio, have invented a new, original, and ornamental Design for an Aeroplane, reference being made to the accompanying drawing, forming a part thereof.

Fig. 1 is a side elevational view of an aero-

plane embodying the design of the invention.

Fig. 2 is a top plan view of the same.

Fig. 3 is a front elevational view of the same.

Fig. 4 is a rear elevational view of the same.

I claim:

The ornamental design for an aeroplane, as shown.

JEAN A. ROCHE.
